UNITED STATES PATENT OFFICE.

FRANK GOGER, OF PATERSON, NEW JERSEY.

MIXING AND KNEADING MACHINE.

1,228,550.

Specification of Letters Patent. Patented June 5, 1917.

Application filed September 29, 1916. Serial No. 122,809.

To all whom it may concern:

Be it known that I, FRANK GOGER, a subject of the Emperor of Austria, residing at Paterson, in the county of Passaic and State 5 of New Jersey, have invented certain new and useful Improvements in Mixing and Kneading Machines, of which the following is a specification.

The object of this invention is to provide 10 a machine for mixing and kneading viscous materials, and especially dough, whereby these treatments may be effected with greater thoroughness and expedition than is possible by machines at present in use. My 15 machine distinguishes from those heretofore devised in that the agitators coact, in effecting the mixing and kneading, to tear apart or shred the materials when they have reached the more or less viscous state, thus 20 to enhance the thoroughness of the action and consequently quicken the treatment. This result I have obtained by providing, in a suitable receptacle for the materials to be mixed and kneaded, a pair of agitators jour- 25 naled on horizontal axes and arranged in parallel planes, said agitators being substantial counterparts of each other and each having a series of counterpart beaters projecting alternately in opposite directions 30 from the axis of said agitator, each beater of one agitator being arranged to pass be- 35 tween two beaters of the other in their rotation, together with means to rotate said agitators in the same direction and at the same speed. In the preferred form each beater is substantially U-shaped so that the beaters at all points play in close relation 40 to those of one agitator to those of the other and may be adapted to play also in close relation to the inner surfaces of the receptacle.

In the accompanying drawing,

Figure 1 is an end elevation of the machine;

Fig. 2 is a transverse sectional view on line 45 2-2 of Fig. 3;

Fig. 3 is a plan; and,

Figs. 4 and 5 illustrate details.

In a pair of standards *a* is supported the receptacle *b* preferably in such manner that 50 it may be tilted to discharge its contents; that is, said receptacle is hung in the standards on trunnions *c*, and is provided with a toothed segment *d* secured to one end and a worm *d'*, meshing with said segment and 55 journaled in the adjoining standard, whereby to move the receptacle on its trunnions

from the position shown in Fig. 1 to that shown in Fig. 2.

In plan the receptacle is rectangular; in end elevation, its bottom has each half 60 formed as part of a cylinder.

In the end walls of the receptacle are journaled trunnions *e* which are held in place by the screws *f* entering circumferential grooves *g* in said trunnions; the inner end of each 65 trunnion is flattened, as at *h*. There are two pairs of these trunnions, arranged on parallel axes. Each pair of trunnions carries an agitator. The agitators are counterparts of each other, each consisting of a series of 70 preferably U-shaped beaters *i* which are counterparts of each other, project alternately in opposite directions from the axis of the agitator and are arranged in the same plane. Each two adjoining (oppositely pro- 75 jecting) beaters are joined by the axial portion *j*, which in the present construction is integral therewith. Having placed the agitators in the receptacle, the trunnions *e* are entered into their bearings with their inner 80 ends entered in holes *h'*, of similar cross- sectional shape, in the axial parts of the end legs (Fig. 4) of the agitators. The agitators are so arranged with reference to each other that in their rotation the beaters of 85 the one play between the beaters of the other and near the axis of rotation thereof.

On each trunnion *e* in each pair is fixed a spur-wheel *k*. Meshing with these is a gear wheel *l* journaled on the adjoining 90 trunnion *c* and having a sprocket-and-chain connection *m* with a suitably driven drive- shaft *n*. The spur-wheels *k* are of the same size, in consequence of which and their being in common geared with the wheel *l* the 95 agitators are rotated, as stated, at the same speed and in the same direction.

The end legs of each agitator further are preferably knife-shaped in cross-section 100 (Fig. 5) and bear flat against the end walls of the receptacle *b*, so as to clear the same of adhering material. Moreover, the radius of each agitator is preferably such that each beater thereof as it rotates will move in close proximity to the corresponding part-cylindrical half of the bottom of the receptacle; thus, particularly as the beaters are sub- 105 stantially U-shaped, practically every part of the material in the receptacle is within the range of agitation.

The arrangement (maintained by the gearing) of the agitators in parallel planes 110

- and their rotation in the same direction and at the same speed, taken with the beaters alternately projecting oppositely from the axis of each agitator and the beaters of one 5 playing between the fields of rotation of the beaters of the other, has the very important advantages already indicated, to wit, that, since each agitator tends to carry around its own axis approximately one-half 10 of the material, and the masses of material thus respectively influenced by the agitators are brought together where their beaters pass each other and then, momentarily formed into one mass, are torn into fragments 15 or shreds, which again form into masses to be respectively carried around again by the agitators, the mixing and kneading is very thorough and consequently considerably expedited.
- 20 When the treatment is completed and the receptacle is to be discharged of its contents, it is tilted to the position shown in Fig. 2, whereupon the agitators are turned more or less slowly to clear them and the receptacle of the material; the delivery of the material is facilitated by the fact that the agitators rotate in the same direction, it being noted that the receptacle is tilted op- 25

positely to the direction of working rotation of the agitators. Preferably, each agitator 30 is formed from a single length of metal bent into the shape required to produce the U-shaped beaters and the axial portions *j*.

Having thus fully described my invention, what I claim as new and desire to secure by 35 Letters Patent is:

In combination, a receptacle, a pair of substantially counterpart agitators journaled in said receptacle on horizontal parallel axes and each including a series of 40 substantially counterpart U-shaped beaters projecting alternately in opposite directions from the axis of said agitator and alined axial portions *j* alternating with said beaters and spaced from each other, said agitators being arranged in substantially parallel planes and so that each beater of either 45 is opposite the corresponding beater of the other and so that on the rotation of the agitators the beaters of either move between 50 the beaters, and near to the axis, of the other agitator, and means to rotate said agitators in unison in the same direction and at the same speed.

In testimony whereof I affix my signature. 55
FRANK GOGER.
